UNITED STATES PATENT OFFICE.

WILLIAM H. BOZARTH, OF VINELAND, NEW JERSEY.

BATHTUB SEAT.

Application filed June 17, 1925. Serial No. 37,834.

My invention relates to bath tub seats, and particularly to a seat adapted to be supported within a tub of the built-in, roll rim, or other standard type, and suspended from the rim edge.

An object of this invention is to provide a seat which is suspended from the rim edge of tub and is at the same time supported upon the side wall, thus distributing the bearing of the supporting parts upon the tub and obviating the necessity of using hooks or other members caught around the rim of the tub and engaging with the porcelain lining at the edge thereof.

A further object resides in so constructing and mounting the parts that the seat can be readily and quickly adjusted to various widths of tubs and the seatings can be locked to retain the adjustment.

A still further object is to so construct the parts that the seat is of simple and inexpensive construction requiring a minimum of labor in assembling, and further that the parts can be packed and shipped in a semi-assembled condition to thus save space.

With the above and other objects in view, which will be apparent to those skilled in the art, this invention includes certain novel features of construction and combinations of parts which will be hereinafter described in connection with the drawing.

In the drawing:

Figure 1 is a transverse sectional view through a bath tub showing my improved seat fitted in position for use.

Fig. 2 is a perspective view of the supporting parts in their disassembled relation.

Fig. 3 is a fragmentary sectional view to better show the manner of assembling the parts.

The seat 1, of wood or any other suitable material, is made of any desired shape and is somewhat shorter than the transverse width of the narrowest tub with which the seat might be used. Guide clips 2 and 3, preferably bent up of sheet metal after the manner illustrated in Fig. 2, are secured on the lower side of the seat member 1 adjacent the ends thereof and preferably in alignment, these guide clips being provided with openings 4 to receive screws or other fastenings by which they are secured in place. Extension bracket members 5 and 6, preferably also made of sheet metal, are provided with rib portions 7 to fit within the openings of the guide clips 2 and 3, and these ex-

tension brackets have the side flanges thereof fitted in grooves formed in the seat member 1 beneath the guide clips 2 and 3. The grooves within the seat member are preferably made of such depth that the guide clips 2 and 3 will tighten down against the side flanges 8 of the extension brackets 5 and 6.

The extension brackets 5 and 6 have the connecting hooks 9 at their outer ends, and the bosses 10 are provided on opposite sides of the hook portions. Supporting brackets 11 and 12, preferably made up of sheet metal bent to be substantially U-shaped in cross section, are provided with supporting hooks 13 at their upper ends, these supporting hooks being widened out as at 14 at their bill ends to give a broad bearing portion. Adjacent the lower extremities these supporting brackets 11 and 12 have the openings 15 formed through their closed sides, these openings being of such length that the hook ends 9 of the extension brackets 5 and 6 can be fitted therethrough and the bills of the hook ends will retain the supporting brackets upon the extension brackets. The bosses 10 on the hook ends 9 engage with the inner sides of the U-shaped form of the supporting brackets 11 and 12 and frictionally hold the parts in place.

Cushion blocks 16, of rubber or other suitable material are shaped to conform substantially with the widened bearing portions 14 of the supporting hooks 13, and have ribs 17 thereon to fit within the U-shaped portions of the hooks 13 so that the cushion blocks are held in place. Cushion blocks 18 are provided with ribs 19 to fit within the U-shaped opening of the body of the supporting brackets adjacent the other extremities thereof, and the material forming the supporting brackets may be bossed in as at 20 to engage the portion 19 of the cushion block to aid in retaining the same in place.

In the use of my improved structure the parts are assembled as shown in Fig. 1 and the extension brackets 5 and 6 are adjusted so that the supporting brackets 11 and 12 will fit the tub after the manner illustrated, these seatings of the extension brackets being locked and retained by tightening down the fastenings received through the openings 4 of the guide clips 2 and 3. When the seat is fitted in place the cushion blocks 16 fit upon the upper rim edge of the tub to suspend the seat and the cushion blocks 18 bear

against the inner side wall of the tub, which wall is usually inclined after the manner shown in Fig. 1, to thus insure that the hook ends of the supporting brackets will not be displaced from the rim of the tub and to also aid in supporting the weight of a person sitting upon the seat member 1. In this fitting and use of my structure the weight is borne entirely upon the cushion blocks 16 and 18, and these blocks are supported upon the porcelain or enameled surfaces of the tub away from any edge portions thereof, thus guarding against cracking, peeling, or otherwise injuring the surface.

15 When the seat is to be packed for shipment or handling, the extension brackets 5 and 6 can be withdrawn from the guide clips 2 and 3 and disassembled from the supporting brackets 11 and 12. The extension brackets can be fitted with their rib portions 7 in the sides of the U-shaped body of the supporting brackets and the supporting brackets can then be placed on the underside of the seat member 1 adjacent the guide clips 2 and 3, and the entire structure can be packed in a space or container only slightly larger than the seat member 1 and of a thickness corresponding to the thickness of the seat member with the guide clips thereon. The seat member 1 might be covered with sheet cork or a cork material, can be treated with celluloid coating, or can be painted or surfaced in any other desired manner, and the metal portions can be readi- 35 ly nickel plated or finished in any other desired manner.

While I have herein shown and described only certain specific embodiments of my invention and have suggested only certain possible modifications, it will be appreciated that changes and variations can be made in the form, construction, and arrangement of parts without departing from the spirit and scope of my invention.

45 I claim:

1. A bath tub seat comprising an elongated seat portion, guide clips carried by said seat portion adjacent the ends thereof, extension brackets adjustably mounted in the guide clips and provided with upwardly disposed hooks at their outer ends, and a

pair of supporting brackets each provided with a supporting hook at one end having openings formed laterally through the bodies thereof adjacent the remaining ends to receive the hook ends of the extension brackets. 55

2. A bath tub seat comprising an elongated seat portion, guide clips carried by said seat portion adjacent the ends thereof, extension brackets adjustably mounted in the guide clips and provided with hooks at their outer ends, a pair of supporting brackets each provided with a supporting hook at one end having openings formed laterally through the bodies thereof adjacent the remaining ends to receive the hook ends of the extension brackets and lateral extensions on the hook ends to frictionally engage with the supporting brackets to retain the hook ends in place. 70

3. A bath tub seat comprising an elongated seat portion, a pair of sheet metal guide clips having elongated guideways therein mounted on the under side of said seat portion adjacent the ends thereof and substantially in alignment, sheet metal extension brackets having rib portions to fit the guideways of the guide clips and provided with side flanges to be engaged frictionally by guide clips, said extension brackets having hooks at their outer ends and being bossed on the sides of the hooks, a pair of sheet metal supporting brackets of elongated form substantially U-shaped in their body portions and each having one extremity shaped to provide a supporting hook with a widened bearing end, said supporting brackets each having an opening through the back of the body thereof at a location spaced 90 from the straight end to receive the hook end of the extension bracket, blocks to fit the bearing ends of the supporting hooks provided with ribs to frictionally hold within the U-shaped form of the supporting brackets, and cushion blocks provided with ribs to fit within the body of the supporting brackets adjacent the remaining extremities. 95

In testimony whereof I hereunto affix my signature.

WILLIAM H. BOZARTH.
